WAINWRIGHT B. GERVAIS, OF CHICAGO, ILLINOIS, ASSIGNOR TO VARIETY MANUFACTURING COMPANY, OF CHICAGO, ILLINOIS, A CORPORATION OF ILLINOIS.

FIREPROOF GUIDEWAY FOR DOORS AND SHUTTERS.

1,131,924.

Specification of Letters Patent.

Patented Mar. 16, 1915.

Application filed March 26, 1914. Serial No. 827,380.

To all whom it may concern:

Be it known that I, WAINWRIGHT B. GERVAIS, a citizen of the United States, residing at Chicago, in the county of Cook and State of Illinois, have invented certain new and useful Improvements in Fireproof Guideways for Doors and Shutters, of which the following is a full, clear, concise, and exact description, reference being had 10 to the accompanying drawings, forming a part of this specification.

My invention relates to an improved construction of guideway for metallic doors and shutters by which the parts of the guideway 15 may move freely relatively to each other and relatively to the support of the guideway when subjected to a dangerous rise of temperature.

When guideways of the kind under consideration are constructed without provision 20 for permitting movement of one part relatively to another when subjected to high temperature, as for example, when a fire is in progress on one side of a dividing wall 25 through which an opening is formed protected by a fireproof shutter or door, the guideways for the door or shutter are apt to buckle, and thus either interfere with the proper operation of the door or shutter or 30 form an opening between the edge of the door or shutter and the wall through which the fire may pass, or both, and it is to provide against this result that the parts of the 35 guideway are made so they may move relatively to each other when subjected to a dangerous rise in temperature.

My present invention consists in providing 40 layers of filling material between the adjacent surfaces of the parts of the guideway, so that the clamping devices employed to secure the parts of the guideway together will firmly clamp these parts against the intermediate filling layers. The devices employed for securing the parts of the guideway together are preferably contained in 45 enlarged openings through the parts of the guideway, so that ready movement of the parts relatively to each other may be facilitated when the parts are otherwise released 50 from each other. In practice, I find it desirable to apply the layer of filling material directly to the surface of the parts of the guideway, this filling material having a low melting point, so that when the guideway is 55 subjected to a dangerous rise in temperature,

the layers of material will melt out from between the parts of the guideway and thus release them from the clamping action of the devices normally holding the guideway together, and in this released condition the 60 parts of the guideway may move freely relatively to each other, so that any unequal contraction or expansion of the parts will not cause the guideway to buckle.

The several drawings illustrating my invention are as follows:

Figure 1 shows in elevation a metallic roller shutter provided with guideways in accordance with my invention; Fig. 2 is an enlarged sectional view taken along the line 70 2-2 in Fig. 1, showing the construction of the guideway itself; and Fig. 3 is a sectional view of the parts shown in Fig. 2, taken along the line 3-3.

Similar numerals refer to similar parts 75 throughout the several views.

As shown in Fig. 1, a wall 1 is provided with an opening 2 therethrough, which opening may be closed by means of a metallic roller shutter 3. The edges of the shutter 3 80 are received in guideways 4 and 5 by which the edges are held in closed relation to the wall 1 when the shutter is closed.

As shown in Figs. 2 and 3, each guideway 85 consists of an angle-bar 6 secured to the wall 1 by means of bolts 7, and to the outstanding leg of this angle-bar two other angle-bars 8 and 9 are secured, either by bolts or by rivets 10, as desired, these angle-bars being of such proportions that their outstanding 90 legs form a channel guideway for the edge of the shutter 3. The angle-bars 8 and 9 are provided with slots 11 and 12 for receiving the rivets 10, with the exception of the upper one of such rivets in each guideway, 95 and as a result, when the angle-bars are free to move relatively to each other, the slots 11 and 12 readily permit this movement. The bolts 7 are similarly provided with slots in the leg of the angle-bar 6 adjacent to the 100 wall 1, so that said angle-bar may move relatively to the wall when expanded and contracted.

The angle-bars 8 and 9 have coated upon 105 their surfaces adjacent to the angle-bars 6 and 8 respectively layers 13 and 14 of filling material sufficiently hard under normal temperatures to properly hold the guideway in position, but having a low enough melting point so that the application of a dangerous 110

rise of temperature will melt the filling material and thus loosen the clamping bolts or rivets and permit motion of the parts of the guideway relatively to each other. The 5 angle-bar 6 may be similarly provided upon its surface adjacent to the wall 1 with a layer of filling material 15. This material may consist of asphalt, pitch, tar, or similar substances mixed with solvent or oil and other hardening materials, such, for example, as resin, so that the compound may have the desired consistency and melting point, as a result of which it may be applied as a thick paint to the surfaces to be coated therewith. 10 It is immaterial what the nature of this compound is, as long as it is readily fusible or disintegrable by the application of a dangerous rise in temperature.

The essential feature of the invention is 20 that the parts of the guideway shall be separated by filling material which will be readily fused or disintegrated by the application of a dangerous rise in temperature, so that the use of special fastening devices 25 may be done away with. While the fusible material is a spacer for the metallic members, I prefer to have the fusible material carried by the metallic members in the form of a coating which may be readily applied 30 to said metallic members in any suitable way, such for instance as by dipping in a bath of the fusible material in a liquid state, or by coating the metallic members in any other suitable manner. As a result, the parts 35 of the guideway may be prepared in the shop before shipment, and the expense involved is trifling compared with that involved in using some of the heat-responsive fastening devices heretofore employed.

40 It is immaterial whether the parts of the guideway be secured together by bolts or rivets, as the result will be the same regardless of the nature of the fastening devices, as long as the parts prepared as described 45 above are rigidly secured together in any manner known in the art. It is also immaterial what the particular construction of the guideway may be or how the guide for the door or shutter is formed as long as the 50 parts of the guideway are provided on their adjacent surfaces with layers of readily fusible or disintegrable material, as described above.

55 Inasmuch as the fusible material lies between the metallic members, it is housed and protected thereby and cannot become broken off or dislodged by blows struck against the exterior of the structure. It is preferred to have the fusible material extend the length

of the surface to which it is applied, in order 60 that an abnormal rise in temperature will be conducted quickly throughout the fusible material.

What I claim is:

1. In a guideway for doors or shutters, the 65 combination of a plurality of metal bars extending longitudinally of the guideway, layers of filling material between adjacent surfaces of said bars and adapted to be disintegrated by the application of a dangerous 70 rise in temperature, and clamping devices for holding the bars together.

2. In a metallic guideway for doors or 75 shutters, the combination of a plurality of metal bars, a coating of material of low melting temperature on adjacent surfaces of said bars, said coatings being of material thicknesses and spacing the bars, and fastening devices for holding the bars together.

3. In a fireproof guideway, the combination 80 of a plurality of metallic bars, fastening devices for securing the bars together, said bars having clearance openings in them around the fastening devices to permit movement of the bars relatively to each other 85 when the bars are released from each other, and layers of material between adjacent surfaces of said bars, said material being disintegrable by the application of a dangerous rise of temperature.

4. A bar for a metallic guideway having 90 one of its faces provided with a coating of material readily disintegrable by a dangerous rise of temperature, said coating having a material thickness and extending throughout substantially the length of the face to which it is applied.

5. In a fireproof structure, a pair of metallic members, means rigidly fastening the members together, and a spacer interposed 100 between the members, said spacer having a low melting point, substantially as and for the purpose described.

6. In a fireproof structure, a pair of metallic members, means rigidly fastening the 105 members together, and a spacer for said members, said spacer having a low melting point and in the form of a coating on each of the adjacent faces of the metallic members and extending substantially throughout 110 the length of said faces.

In witness whereof, I hereunto subscribe my name this 17th day of March, A. D. 1914.

WAINWRIGHT B. GERVAIS.
